(57) **CLAIM**

The ornamental design for a staggered paper tray, as shown and described.

DESCRIPTION

FIG. 1 is a right front isometric view of a staggered paper tray;

FIG. 2 is a top plan view of the staggered paper tray;

FIG. 3 is a bottom plan view of the staggered paper tray;

FIG. 4 is a left side elevation view of the staggered paper tray;

FIG. 5 is a right side elevation view of the staggered paper tray;

FIG. 6 is a rear side elevation view of the staggered paper tray;

FIG. 7 is a front side elevation view of the staggered paper tray; and,

FIG. 8 is another top plan view of the staggered paper tray, shown in a state of use with two pieces of paper.

The dash-dash broken lines showing two pieces of paper in FIG. 8 depict environmental subject matter that forms no part of the claimed design.

1 Claim, 8 Drawing Sheets
